UNITED STATES PATENT OFFICE.

ROBERT E. B. ALLEN, OF PENSACOLA, FLORIDA.

CUFF-BUTTON.

1,398,954.

Specification of Letters Patent.

Patented Dec. 6, 1921.

Application filed March 7, 1921. Serial No. 450,201.

To all whom it may concern:

Be it known that I, ROBERT E. B. ALLEN, a citizen of the United States, residing at Pensacola, in the county of Escambia and State of Florida, have invented new and useful Improvements in Cuff-Buttons, of which the following is a specification.

The present invention relates to cuff buttons, and particularly to safety devices which will insure against the loss of the button after it has been placed in the cuff, the construction being such, however, as not to interfere with the ready insertion or removal of the button from the cuff.

While the invention will be described and shown, as applied to cuff buttons, it will be understood that the safety features of the device may be applied to other articles of jewelry or ornamentation to prevent loss, and is not confined to the specific article herein illustrated.

I accomplish the object stated by providing the shank of the button with resilient or spring means which serves to hold in proper position a bar or button member interlocked with the shank of the main button member, so that until that locking bar is unseated against the pressure of the spring and moved to unlocked position, it cannot escape from the shank and will, when in place, hold the button surely in the cuff.

In order that the invention may be clear to those skilled in the art, I have shown in the accompanying drawings one embodiment of my invention, but this, it will be understood, is illustrative only and in no sense restrictive, as it is obvious that mechanical expedients other than those herein disclosed and the equivalent of those used to illustrate the invention may be adopted and still be within the range my invention.

Referring to the drawings:

Figure 1 is a view, in side elevation, of a cuff button embodying my invention;

Fig. 2 is a top plan view;

Fig. 3 is a view in elevation at right angles to Fig. 1;

Fig. 4 is a cross section on substantially the line 4-4 of Fig. 3 looking down;

Fig. 5 is a view in side elevation similar to Fig. 3 with the locking member in position for removal.

Referring to the drawings by numbers, like numbers indicating like parts in the several views, 10 denotes a button member which may be of any suitable shape and de-

sign. Extending from the underside of the member 10 is a plurality of loops 11, two being shown in the present instance. The said loops 11 lie parallel to each other and are closed at their outer ends preferably by being turned back as shown. Between their ends and preferably near the point of attachment of the loops 11 to the button member 10 the arms of the loops are provided with offsets or swells 12 to give an enlarged opening or passage-way in each loop, these offsets 12 being disposed directly opposite each other as shown.

Housed within the loops 11 and preferably secured at one end to the button member 10, is a spring 13 herein shown as a spiral spring of a sufficient length and resiliency to extend when expanded to the ends of the loops, as shown in Fig. 1, but being capable of compression to a point inside of the offsets 12 formed in the loops 11 as shown in Fig. 5.

The other member of the button consists of a bar 14, having between its ends a bulge 80 or enlargement 15, preferably symmetrically formed as shown, and of a size which, while it will slide freely between the loops 11 is too large to be withdrawn laterally through those loops. The said bar 14 is engaged with the loops 11 by being passed through the offsets or passage-ways 12 in the said loops until its enlarged section 15 is midway between the loops 11, whereupon the spring 13 will be released and the bar 14 90 forced downwardly by the spring to the ends of the loops 11, where, by reason of the enlargement 15, it will be locked against displacement laterally from the loops and by reason of the spring 13 will be held against 95 longitudinal displacement in the loops.

In order that the spring 13 may be conveniently manipulated, I provide a coil, preferably the coil at the free end of the spring, with lateral projections 16, which 100 project beyond or outside of the loops 11, so as to form finger holds for compressing the spring down against the button member 10, when the parts are assembled or disassembled. Preferably, the projections 16, four 105 of which are shown, although a single projection at one side of the spring would suffice, are so shaped as to overhang the legs of the loops 11 and prevent lateral displacement of the free end of the spring 13.

In Fig. 4 I have shown a slightly different mechanical arrangement of the spring

manipulating projections, there being shown in that figure a follower plate 17, said follower blade resting upon the free end of the spring 13 or, if desired, being secured to that free end and having lateral overhanging projections 18, which extend beyond the loops 11 and are interlocked therewith.

The application of the button to a cuff will, it is believed be obvious. The locking bar or member 14 will be removed by compressing the spring 13 to the point where the bar 14 may be removed laterally through the offsets 12. The loops 11, which form the shank of the button will then be threaded or thrust through the buttonholes in the cuff. The spring 13, by means of the lateral projections at its free end, will again be compressed below the offsets 12 and the locking bar or member will then be passed laterally through the offsets, until its enlarged section 15 lies between the loops. The spring 13 will then be released, carrying the locking bar to the ends of the loops, from which position it cannot escape.

It will be observed that by arranging the parts as described, a button is provided which may be very quickly and easily inserted in a cuff, as the loops which form the shank, and the spring, are so arranged as that there is no interference with the operation of threading the shank through the buttonholes, and when the locking bar or member has been seated in the ends of the loops, and is held there by the spring, there is no danger of separation of the parts, as the bar cannot escape laterally and cannot be accidentally brought to its position of removal at the offsets in the loops near their point of attachment to the main button member.

While I have shown the invention as applied to a rigid shank type of button, it will be obvious that the loops and the contained spring which form the shank could be mounted upon a suitable head or base and that head or base linked to the ornamental part of the cuff button in the usual manner, so as to provide, if desired, a loose shank type of button.

I claim:

1. In a device of the class described, a button member, a shank member, a second button member shiftable lengthwise of said shank member, means on said second member to prevent its lateral displacement relative to said shank member except at a predetermined point, and means acting on said second button member normally to maintain said second button member out of line with the predetermined point of lateral displacement.

2. In a device of the class described, a button member, a shank member, a second member interlocked against lateral displacement except at a predetermined point but

freely movable lengthwise of said shank member, and resilient means pressing against the second button member normally to maintain said second member out of line with the predetermined point of lateral displacement. 70

3. In a device of the class described, a button member, a shank member comprising an open loop, a second button member interlocked against lateral displacement except 75 at a predetermined point but freely movable lengthwise of said loop, and resilient means pressing against the second button member normally to maintain said second button member out of line with the predetermined 80 point of lateral displacement.

4. In a device of the class described, a button member, a shank member comprising a plurality of open loops, a second button member shiftable lengthwise of said loops, 85 means to prevent lateral displacement of said second button member in said loops except at a predetermined point, and a spring pressing against the second button member normally to maintain said second button 90 member out of line with the predetermined point of lateral displacement.

5. In a device of the class described, a button member, a shank member comprising a plurality of open loops, a second button 95 member shiftable lengthwise of said loops, means on said second button member to prevent its lateral displacement in said loops except at a predetermined point, and a spring normally to maintain said second 100 button member out of line with the predetermined point of lateral displacement.

6. In a device of the class described, a button member, a shank member comprising an open loop having between its ends a laterally enlarged passage, a second button member freely shiftable lengthwise of said loop member but laterally displaceable only through the laterally enlarged passage in said loop member, and means normally to maintain said second button member out of line with the laterally enlarged passage in said loop member. 105

7. In a device of the class described, a button member, a shank member formed of a plurality of loops having laterally offset sections between their ends to provide enlarged lateral passages, a second button member having an enlarged section and freely shiftable lengthwise of said loop members but laterally displaceable only through said enlarged passages, and a spring housed within said loop members normally to maintain said second button member out of line with said laterally enlarged passages in said loop member. 115 120 125

8. In a device of the class described, a button member, a shank member comprising two loops secured to said button member and having closed ends, said loops having out- 130

wardly bent sections between their ends to provide laterally enlarged passages; a button bar having an enlarged section between its ends sliding freely lengthwise of said loops and removable laterally through said enlarged passages, a spring housed between said loops normally to maintain said button bar out of line with said laterally enlarged passages, and means extending outside of 10 said loops to compress said spring.

9. In a device of the class described, a button member, a shank member comprising two loops secured to said button member and having closed ends, said loops having

outwardly bent sections between their ends 15 to provide laterally enlarged passages; a button bar having an enlarged section between its ends sliding freely lengthwise of said loops and removable laterally through said enlarged passages, a spring housed between said loops normally to maintain said button bar out of line with said laterally enlarged passages, and a follower plate having portions extending outside of said loops to compress said spring.

In testimony whereof I have hereunto set 20
my hand.

ROBERT E. B. ALLEN.
